(57) **ABSTRACT**

The neck warmer includes a collar fabricated from warm, soft material and having free ends provided with hook and loop fasteners to allow the collar to be fastened closely around a wearer's neck. The collar has a slight V-shape at its front. Ornamental pieces can be optionally attached to the front of the collar to create a desired fashionable effect.

NECK WARMER

BACKGROUND OF THE INVENTION

1. Field of the Invention

The present invention generally relates to wearing apparel, and more particularly to a neck warmer that can be worn around the neck as a scarf or collar and has ancillary removable, ornamental attachments.

2. Description of the Related Art

There are many times when one is in need of a garment to protect the neck from the cool air. Heretofore, the conventional scarf has been employed to accomplish this task. Unfortunately, the design of the conventional scarf presents some drawbacks for the wearer. For example, the scarf must be wrapped around the neck to attain maximum protection. This scenario presents a somewhat bulky and uncomfortable scarf layer at the neck. Furthermore, it is difficult to wrap the scarf in a manner wherein the free ends hang evenly, thus presenting a somewhat unfashionable look. Tucking the free ends inside other clothing is not a satisfactory solution in that the ensuing bulkiness is unsightly. The art would certainly welcome a non-bulky neck wrap that could be easily donned, removed and provided with interchangeable ornamental pieces for projecting a fashion statement.

Thus, a neck warmer solving the aforementioned problems is desired.

SUMMARY OF THE INVENTION

The neck-warmer comprises a collar fabricated from warm, soft material having free ends provided with hook and loop fasteners to allow the collar to be fastened closely around a wearer's neck. The collar has a slight V-shape at its front. Ornamental pieces can be optionally attached to the front of the collar to create a desired, fashionable effect.

Accordingly, the invention presents a neck warmer that does not require tying or odious wrapping. The neck warmer is easy to don and remove. Ornamental adjuncts can be optionally attached to the collar to create a desired fashion look. The invention provides for improved elements thereof in an arrangement for the purposes described that are inexpensive, dependable and fully effective in accomplishing their intended purposes.

These and other features of the present invention will become readily apparent upon further review of the following specification and drawings.

BRIEF DESCRIPTION OF THE DRAWINGS

FIG. 1 is an environmental, perspective view of a neck warmer according to the present invention, shown without ornamental attachments.

FIG. 2 is an environmental, perspective view of a neck warmer according to the present invention, shown with one ornamental attachment.

FIG. 3 is an environmental, perspective view of a neck warmer according to the present invention, shown with two ornamental attachments.

FIG. 4 is an exploded rear view of a neck warmer according to the present invention, shown with two ornamental attachments.

Similar reference characters denote corresponding features consistently throughout the attached drawings.

DETAILED DESCRIPTION OF THE PREFERRED EMBODIMENTS

Attention is first directed to FIG. 1, wherein a first configuration of a neck warmer of the present invention is generally indicated at 10. The neck warmer 10 is shown utilized as a collar or neck-wrap 12 with no attachments. The configuration shown in FIG. 2 incorporates a single ornamental tie 22

2

that can be optionally attached to collar 12. FIG. 3 shows the collar 12 configured with two optionally attached ties 22, 24.

As best seen in FIG. 4, collar 12 comprises a single, elongate member having front and rear surfaces and free ends 14 and 16. A plurality of fasteners 18 (preferably hook and loop) are disposed adjacent each respective free end on opposing surfaces. This arrangement allows a wearer to quickly and easily fasten the collar around his/her neck. A shallow V-shaped configuration 12a is formed on the lower edge of collar 12. The V-shaped configuration can be tucked beneath the wearer's clothing to hold the bottom edge of the collar securely around the wearer's neck. Another hook and loop fastener 20 is disposed on the inner surface of collar 12 adjacent the V-shaped configuration for reasons as will be explained below. As indicated above, two ornamental ties 22 and 24 are provided for optional attachment to collar 12. Each ornamental tie is provided with a respective hook and loop fastener 26, 28 on one surface thereof. The respective ornamental ties are attached to the collar by means of hook and loop fasteners 20, 26 and 28. Although hook and loop fasteners are preferred, it should be recognized that other suitable fasteners (buttons, zippers, etc.) could be utilized if suitable.

Preferably, collar 12 will have a circumference of approximately eight to twenty-four inches and a width of 3 to 6 inches. The removable ornamental ties will have a length of eight to twelve inches. Both collar and ornamental ties are fabricated from a suitable soft, pliable material such as nylon, fur, cashmere, cotton, etc. and can be made in various colors. The ornamental ties can be further adorned with decorative ends that may include tassels, beads, strands and the like to satisfy different aesthetic desires.

It is to be understood that the present invention is not limited to the embodiments described above, but encompasses any and all embodiments within the scope of the following claims.

I claim:

1. A neck warmer, comprising:
a one-piece collar having a top edge and a substantially parallel bottom edge, a front surface, a rear surface, a first free end and a second free end, the bottom edge having a shallow substantially V-shaped configuration formed at a central area of the collar, wherein the remainder of the collar retains the parallel edges;

first fastener devices disposed on the front surface of the collar adjacent the first free end;
second fastener devices disposed on the rear surface of the collar adjacent the second free end;

third fastener devices disposed solely on the rear surface of the collar adjacent the shallow substantially V-shaped configuration at the central area of the collar; and
further including at least one ornamental tie removably attached to the third fastener at the central area.

2. The neck warmer according to claim 1, wherein said first, second and third fastener devices are hook and loop fastener devices.

3. The neck warmer according to claim 1, wherein said collar is fabricated from a soft, pliable material.

4. The neck-warmer according to claim 1, further including two ornamental ties removably attached to said collar at the central area.

5. The neck-warmer according to claim 1, wherein said collar has a circumference of approximately eight to twenty-four inches and a width of approximately 3 to 6 inches.

6. The neck warmer according to claim 2, wherein said at least one ornamental tie having a front surface, a rear surface and a length of approximately eight to twelve inches; and
a fourth hook and loop fastening device disposed on the front surface of the at least one ornamental tie.
